MULTIPLE ACTION POWER PRESS

Vasili Georgeff, Chicago, Ill., assignor to Danly
Machine Specialties, Inc., Chicago, Ill., a corpora-
tion of Illinois

Application August 23, 1948, Serial No. 45,770

5 Claims. (Cl. 74—40)

1

My invention relates to multiple action power presses and more particularly to a multiple action power press of improved construction making for a stronger crown, simplified assembly and the elimination of overhang at the sides of the crown.

Many forms of multiple action power presses are known to the art. They comprise power presses provided with a plurality of slides in which one is usually adapted to act as a blank holder to grip or hold work while another slide or slides is performing actual shaping or forming operations.

In general the operating mechanism for the slides in the prior art has employed a number of separate cranks usually spaced one from the other in order to give the proper phase relations. This has entailed the employment of a correspondingly large number of linkages which resulted in the provision of an oversized crown having a wide lateral dimension and customary overhang of the main frame of the press to a considerable extent. The massive size of the crown of the press not only increased its cost and difficulty of assembly, but occupied a large floor area in a manufacturing plant where space is frequently at a premium.

It has been suggested by Einar K. Johansen in Patent 2,257,383, that the number of cranks could be reduced by the use of a pair of gears secured to a common crank, which common crank was employed to operate the rocker member for one of the slides. While this construction has been an improvement over some of the prior art, yet the crown of the Johansen press is still formed with an overhang at the sides of the press and the assembly is still complicated. Then too, in the Johansen construction there is considerable lateral thrust in the blank holder drive which reduces correspondingly the vertical thrust desired.

One object of my invention is to provide a multiple action power press having a pair of slides, one of which is driven as a blank holder, and the other of which is driven to do the work, of simplified construction.

Another object of my invention is to provide a double action press employing a double eccentric gear, thus eliminating the use of a plurality of cranks.

2

Another object of my invention is to provide a multiple action power press providing for the dwell of the blank holder slide with a reduced number of linkages and parts all driven from a common prime mover in which the forces are applied substantially vertically, thus reducing lateral thrust.

A further object of my invention is to provide a double action power press in which the inner or working slide is driven by an eccentric gear carrying a second eccentric driving the blank holder slide through a linkage to provide the proper phase relations between the two slides.

Still another object of my invention is to provide a multiple action power press having a crown of less width than the crowns of the presses of the prior art, yet stronger in construction.

Another object of my invention is to provide a multiple action power press in which the assembly of the press is simplified and in which overhanging portions of the crown are obviated.

Other and further objects of my invention will appear from the following description.

In general my invention contemplates the provision of a pair of slides one of which is driven directly by an eccentric and the other is driven by a second eccentric formed integral with the first eccentric upon a gear, through a rocker shaft and an appropriate linkage providing for a proper period of dwell of the blank holder during the working part of the cycle of a second slide. The use of two eccentrics upon a common gear establishes a predetermined phase relation of the movement of the connecting rods or pitmans driven by the eccentrics and avoids the use of plurality of cranks for driving the respective slides.

In the accompanying drawings which form part of the instant specification and which are to be read therewith, and in which like reference numerals are used to indicate like parts in the various views:

Figure 1 is a front elevation of a multiple action power press made in accordance with one embodiment of my invention.

Figure 2 is a fragmentary sectional elevation drawn on an enlarged scale of the crown of the press shown in Figure 1.

Figure 3 is a sectional view taken along the line 3—3 of Figure 2.

Figure 4 is a sectional view taken along the line 4—4 of Figure 2.

Figure 5 is a diagrammatic perspective view showing the driving arrangement for both the inner and outer slides.

Figure 6 is a diagram containing curves showing the travel of the inner and outer slides and their phase relationships.

More particularly, referring now to the drawings, a press frame 10 supports a crown 12 housing the driving mechanism adapted to reciprocate an outer or blank holder slide 14, and an inner or working slide 16. Suitable dies (not shown) are secured to the slides 14 and 16. Bolster 18 is adapted to support coacting dies for cooperation with the blank holding and working dies carried by the slides. A prime mover 20, which may be an electric motor, is mounted on top of the crown of the press to drive a flywheel 22 through a suitable transmission such as V-belts 24. The flywheel 22 is adapted to be clutched and unclutched to a driving pinion for driving the operating mechanism for the slides, as will be pointed out more fully hereinafter. A pair of rocker shafts 26 and 28 are carried in suitable bearings in the crown 12. The shafts 30 and 32 support intermediate gears in the driving gear train. The shafts 34 and 36 mount the main eccentric gear on which is formed a pair of eccentrics having different radii of eccentricity and being angularly displaced one from the other, as will be described more fully hereinafter.

Referring now to Figure 2, the pinion 38 is secured to and driven by a shaft 40, which is in turn driven from the flywheel 22 through an appropriate clutch (not shown), as is well known in the art. The pinion 38 meshes with a gear 42 which in turn meshes with a like gear 44. The gears 42 and 44 are secured to shafts mounted in bearings 46 and 48, to which shafts pinions 50 and 52 are secured for rotation therewith. Pinion 50 meshes with a gear 54 and pinion 52 meshes with a gear 56. A pinion 58 rotates with gear 54 and a pinion 60 rotates with gear 56. The pinion 58 meshes with and drives eccentric gear 62 while the pinion 60 meshes with and drives eccentric gear 64. The eccentric gear 62 is formed with a pair of eccentrics 66 and 68. The gear 64 is formed with a pair of eccentrics 70 and 72. A pitman 74 extends between eccentric 66 and the inner or working slide 16, while pitman 78 connects eccentric 70 to the working slide 16. A crank 82 is carried by rocker shaft 26 for oscillation therewith and a crank 84 is carried by rocker shaft 28 for oscillation therewith. A pitman 86 connects the end of crank 82 to the eccentric 68. A pitman 88 connects the end of crank 84 to the eccentric 72. Rocker shaft 26 is carried in suitable bearings 90 while the rocker shaft 28 is carried in suitable bearings 92. An arm 94 is secured to rocker shaft 26 for oscillation therewith while an arm 96 is secured to rocker shaft 28 for oscillation therewith. The end of crank 94 is connected to one arm 106 of bell crank 108 by a link 98. The end of crank 96 is connected to one arm 108 of bell crank 104 by link 102. The other arm 116 of bell crank 104 is connected to the upper end 112 of the outer or blank holder slide by connecting rod 114. The other arm 116 of bell crank 108 is connected to the upper end 112 of the blank holder slide by connecting rod 118. The crown of the press 12 is secured to the press frame 10 through a plu-

rality of tie rods 11, as can readily be seen by reference to Figures 2 and 4.

The construction of the eccentric gear can readily be understood by reference to Figures 3 and 4 in which the gear 62 is integrally formed with a pair of eccentric hubs forming the large eccentric 66 for driving the pitman 74 and the smaller diameter eccentric 68 for driving the pitman 86.

10 It will also be seen by reference to Figure 4 that the eccentric gear 62 is mounted upon the shaft 34 with the eccentric hubs 66 and 68 directed toward the front of the press. Eccentric gear 64, however, is mounted on shaft 36 with its 15 eccentric hubs 70 and 72 directed toward the rear of the press, that is oppositely from the direction of the extension of the eccentric hubs 66 and 68. This forms a compact crown arrangement and permits the use of larger gears. Crank 82 is 20 bifurcated. The end of pitman 86 is pivotally secured to the end of crank 82 through pin 81. The upper end of pitman 88 is secured to the bifurcated crank 84 through pin 83.

Referring now to Figure 5, which is a diagrammatic view showing the eccentrics, the rocker shaft, the cranks and the linkages of the right hand eccentric gear 64 of Figure 2, the rotation of the eccentric gear 64 will rotate both the large eccentric 70 and the small eccentric 72, thus 25 reciprocating pitman 78 and pitman 88. The difference of the diameters of the eccentrics produces different amplitudes of reciprocation. As can be seen more readily by reference to Figure 2, the angular position of the center of eccentricity of the small eccentric is displaced with 30 respect to the center of eccentricity of the large eccentric, thus changing the phase of reciprocation of the pitman 88 with respect to the reciprocation of the pitman 78. It will be noted, 35 too, that the axis of the rocker shaft 28 is not displaced through a very great distance laterally from the axis of the eccentric gear shaft 36. The arrangement of parts is such that the oscillation of the rocker shaft 28 will bring the linkages into positions in the vicinity of 180° during 40 the period of dwell of the blank holder slide so that the angular motion of the rocker shaft will produce substantially no movement in a vertical direction of the blank holder slide. In the operation of my press lower bell crank lever arm 116 and connecting rod 118 approach forming 45 an angle of 180° with each other, at the same time that crank 96 and link 102 approach forming an angle of 180° with each other, at which time the blank holder slide is very slightly above its bottom dead center. Lower bell crank lever arm 116 and connecting rod 118 reach a position of 180° with respect to each other, that is, bottom dead center, slightly before crank 96 and link 102 form an angle of 180° with each other. When crank 96 and link 102 form an 50 angle of 180° with each other the lower bell crank lever arm 116 and the connecting rod 118 have formed an angle slightly greater than 180° with each other. As crank 96 and link 102 form an angle of 180° with each other the lower bell crank lever arm 116 and connecting rod 118 move back to exact dead center and have 55 slightly passed the dead center position as the oscillation of the crank 96 continues. As the pitman 88 reverses its direction of travel under the influence of the eccentric 72, the rocker shaft 28 reverses the sequence of motions just described. During the period of dwell, therefore, the blank holder will oscillate slightly ad-

ja⁵cent its bottom dead center four times through a very small amplitude. The amplitude of this oscillation is in the order of .003 of an inch and is so small as to be within the range of elongation of the metal of the linkages and the tie rods of the press. As a practical matter the blank holder dwells apparently immovably at bottom dead center to hold the work while work is being performed by the inner slide. The arrangement of parts is such that the rocker shaft driving eccentric, the connection between crank 96 and the link 94 and the connection between lower bell crank arm 116 and connecting rod 118 all arrive in the vicinity of their dead centers at substantially the same time. It is in this manner that the dwell is achieved by a continuously rotating drive with the use of only cranks and links.

The phase relationships of the movement of the blank holder with respect to the inner slide can be readily seen by reference to Figure 6. Starting from top dead center of the inner slide we find that the blank holder slide is already moving downwardly reaching its bottom dead center at approximately 90° at which point the period of dwell starts, during which there is the very slight oscillatory movement through a small amplitude which was described above. The inner slide continues downwardly with simple harmonic motion and performs its work. At about 210° of travel of the eccentric gear the blank holder slide, the driving eccentric actuating which leads the eccentric which drives the inner slide, begins to move upwardly and reaches its top dead center at about 320° while the inner slide continues its upward motion.

It is believed that the operation of my press will be clear from the foregoing description. It will be seen that I have accomplished the objects of my invention. I have provided a multiple action power press having a pair of slides, one of which is driven as a blank holder, and the other of which is driven to do the work, of simplified construction. I have provided a double action power press employing a double eccentric gear thus eliminating the use of plurality of cranks and providing a construction employing a reduced number of linkages and parts. I have provided a double action power press in which the forces are applied substantially vertically, thus reducing lateral thrust and enabling the use of a crown having less width. I have provided a multiple action power press in which the assembly is simplified and in which the overhanging crown portions are obviated.

It will be understood that certain features and sub-combinations are of utility and may be employed without reference to other features and subcombinations. This is contemplated by and is within the scope of my claims. It is further obvious that various changes may be made in details within the scope of my claims without departing from the spirit of my invention. It is, therefore, to be understood that my invention is not to be limited to the specific details shown and described.

Having thus described my invention, what I claim is:

1. A multiple action power press including in combination a frame having a crown, a pair of slides mounted for reciprocation in said frame, a pair of shafts extending across said crown, a pair of gears journaled upon said shafts, means for rotating said gears, each of said gears being formed with a pair of eccentrics, one of said

eccentrics of each gear being angularly displaced from the other of said eccentrics, a pair of rocker shafts carried by said crown each having a pair of cranks, a pair of pitmans connecting one of said slides with a respective pair of eccentrics, a pair of pitmans connecting the other pair of eccentrics to one pair of rocker shaft cranks, a pair of bell cranks mounted for oscillation about said shafts, a pair of links connecting the ends of the other pair of rocker shaft cranks to respective upper arms of the bell cranks and connecting rods connecting the lower arms of said bell cranks to the other of said slides.

2. A power press as in claim 1 in which the rocker shafts are positioned above said gear shafts and the dimensions of the parts are such that as the rocker-shaft-operating pitmans approach bottom dead center said second rocker shaft cranks will approach forming an angle of 180° with the links connecting the upper bell crank arms, and the lower bell crank arms will approach forming an angle of 180° with the connecting rods extending to the second slide whereby said second slide will dwell at a position close to its bottom dead center while said first slide moves with simple harmonic motion.

3. In a multiple action power press a crown, a pair of rocker shafts carried by said crown, a second pair of shafts carried by said crown, a pair of gears journaled about said second shafts, each of said gears being formed with a pair of eccentrics, a pair of slides, a pair of pitmans connecting one pair of said eccentrics to one of said slides, each of said rocker shafts having a pair of cranks, a pair of pitmans connecting the other pair of said eccentrics to one pair of rocker shaft cranks, a pair of bell cranks journaled about said second shafts, links for connecting the other of said rocker shaft cranks to the upper bell crank arms, connecting rods for connecting the lower bell crank arms to the other of said slides, the eccentrics of one of said gears extending toward the rear of said press and the eccentrics of the other of said gears extending toward the front of said press.

4. A multiple action power press including in combination a pair of slides, a pair of eccentrics, means for rotating said eccentrics together, a pitman carried by one of said eccentrics and extending to one of said slides for reciprocating the same with simple harmonic motion, a rocker shaft having a pair of cranks, a pitman for connecting one of said cranks to the other of said eccentrics, a bell crank, a link pivotally connecting the other of said cranks with one of said bell crank arms, a connecting rod between the other of said bell crank arms and the other of said slides, a driven gear journaled upon a shaft, said eccentrics being formed integrally with said gear, one of said eccentrics being of larger diameter than the other and having its center angularly displaced from the other of said eccentrics.

5. A multiple action power press including in combination a pair of slides, a pair of eccentrics, means for rotating said eccentrics together, a pitman carried by one of said eccentrics and extending to one of said slides for reciprocating the same with simple harmonic motion, a rocker shaft having a pair of cranks, a pitman for connecting one of said cranks to the other of said eccentrics, a bell crank, a link pivotally connecting the other of said cranks with one of said bell crank arms, a connecting rod between the other of said bell crank arms and the other of

said slides, a driven gear journalled upon a shaft, said eccentrics being formed integrally with said gear, one of said eccentrics being of larger diameter than the other and having its center angularly displaced from the other of said eccentrics, the pitman for reciprocating one of said slides being disposed about the larger of said eccentrics, and the pitman for operating said rocker shaft being disposed about the smaller of said eccentrics.
